UNITED STATES PATENT OFFICE

2,573,863

COMPRESSOR

Alva E. Mitchell, Philadelphia, Pa.

Application May 19, 1948, Serial No. 27,892

15 Claims. (Cl. 230—20)

1

This invention relates to compressors. It is the principal object of the present invention to provide an improved positive displacement compressor capable of construction by mass production methods, and which will be compact and light in weight.

It is a further object of the present invention to provide a compressor with unloaded starting.

It is a further object of the present invention to provide a compressor having variable capacity, with automatic stroke regulation for modifying the capacity.

It is a further object of the present invention to provide a compressor having improved provisions for controlling the capacity thereof directly from a controlling element.

It is a further object of the present invention to provide a compressor which is inherently balanced and capable of smooth and quiet operation at relatively high speeds.

It is a further object of the present invention to provide a compressor having a simplified form of actuation of the compressor pistons.

Other objects and advantageous features of the invention will be apparent from the specification and claims.

The nature and characteristic features of the invention will be more readily understood from the following description, taken in connection with the accompanying drawings forming part hereof, in which:

Figure 1 is a longitudinal sectional view of a compressor in accordance with the present invention, the valve plate being rotated to show the position of the suction and discharge ports in relation to the cylinders;

Fig. 2 is a transverse sectional view taken approximately on the line 2—2 of Fig. 1;

Fig. 3 is a fragmentary sectional view taken approximately on the line 3—3 of Fig. 2;

Fig. 4 is a transverse sectional view taken approximately on the line 4—4 of Fig. 1;

Fig. 5 is a longitudinal sectional view of a compressor in accordance with the present invention showing one arrangement of automatic unloader and stroke regulator and with the valve plate as seen along the line 5—5 of Fig. 6;

Fig. 6 is a transverse sectional view taken approximately on the line 6—6 of Fig. 5;

Fig. 7 is a transverse sectional view taken approximately on the line 7—7 of Fig. 5;

Fig. 8 is a longitudinal sectional view of a compressor in accordance with the present invention showing another arrangement of automatic unloader and stroke regulator;

2

Fig. 9 is a fragmentary view in elevation illustrating the details of the trunnion pins;

Fig. 10 is a fragmentary sectional view taken approximately on the line 10—10 of Fig. 8, and with the angle plate revolved to the "no-load" position;

Fig. 11 is a fragmentary transverse sectional view taken approximately on the line 11—11 of Fig. 8; and

10 Fig. 12 is a fragmentary sectional view taken approximately on the line 12—12 of Fig. 8 and illustrating the provisions for longitudinal adjustment of the thrust bearing.

It should, of course, be understood that the description and drawings herein are illustrative merely, and that various modifications and changes may be made in the structure disclosed without departing from the spirit of the invention.

15 Like numerals refer to like parts throughout the several views.

Referring now more particularly to the drawings, the compressor in accordance with the present invention preferably includes an exterior cylindrical casing 15 closed at one end by an end closure plate 16, the closure plate 16 preferably being secured in position with respect to the casing 15 such as by longitudinally disposed studs 17, as indicated in Figs. 1 and 5. At the opposite end of the casing 15, a valve plate 18 is provided, in fixed relation to the casing 15. The valve plate 18 is preferably provided with a suction or inlet port 19 having the inner end thereof longitudinally disposed, and with a delivery or discharge port 20 also having the inner end thereof longitudinally disposed. The valve plate 18 is provided with a suitable bearing 21 and a drive shaft 22 is provided which extends centrally through the valve plate 18 and the bearing 21 therein

25 and is journaled at its inner end in a bearing 23 carried by the end plate 16. A seal 24 may be provided, removably mounted in the valve plate 18 for preventing fluid leakage along the shaft 22. Within the casing 15, a cylindrical bearing or

30 wear sleeve 25 may be provided, and, within the sleeve 25, a rotor 26 is carried, the rotor 26 being fixedly mounted with respect to the shaft 22 for rotation therewith. The rotor 26 is provided with a plurality of axially extending bores 27, which 35 serve as working cylinders within the rotor 26, the ends 28 of the bores 27 adjacent the valve plate 18 preferably being tapered and provided with a small cylindrical terminal 29, for communication, as hereinafter explained, with the 40 inlet port 19 and with the discharge port 20.

Packing rings 39 may be interposed between the valve plate 18 and the rotor 26 for preventing fluid leakage.

Within each of the cylinders provided by the bores 27 a piston 31 is mounted for axial reciprocation therein in parallel relation with the shaft 22. Each of the pistons 31, adjacent the valve plate 18 has an end portion 32 complementary to the ends 28 of the bores 27 and may also have a cylindrical terminal 33 filling the space provided by the bore terminal 29 for reducing the clearance volume in the cylinder to a minimum.

Each of the pistons 31 preferably has a connecting rod 34 pivotally connected thereto. The connecting rods 34 are pivotally connected at their opposite ends to bearing rings 35. The bearing rings 35 are supported by bearings shown at 36 in Fig. 1, at 37 in Fig. 5 and at 38 in Figs. 8 and 10, in a cap ring 40. The cap ring 40 may be mounted on trunnions 41 at each side thereof, as illustrated in Fig. 4, or on a plurality of trunnions 42 and 43, as illustrated in Figs. 8 and 10.

The pivotal axis of the cap ring 40, provided by the trunnions 41 or 42 and 43, is located so as to be coincident with the path of the lower end of each connecting rod 34 as each piston passes through the point of top dead-center, so that the top dead-center is fixed regardless of the positioning of the cap ring 40. The cap ring 40 is provided with a pair of curved lugs 45 which are adapted for engagement by transversely movable cam elements 46.

The cam elements 46, as indicated in Figs. 1, 2 and 3, may be mounted for transverse movement with respect to a cam mounting plate 47 carried within the housing 15, the cam elements 46 having guide portions 48 for engagement in parallel slots 49, having limit stops 49^a, in the cam mounting plate 47. Transversely disposed springs 50 may be provided in spring sockets 51 and interposed between the cam elements 46 and longitudinally extending portions 52 of the cam mounting plate 47 for normally urging the cam elements 46 into engagement with the lugs 45 and to a position for unloading with minimum piston stroke.

Referring now more particularly to Figs. 5, 6 and 7 of the drawings, the rotor sleeve 25 is provided with an oil delivery slot 55 which communicates with a groove 56 on the inner face of the valve plate 18, oil passageways 57 being provided in communication with the face of the valve plate 18 and with the bearing 21 in the valve plate 18.

The valve plate 18 may also be provided with a relief valve plate 60 axially movable in the valve plate 16 and normally impelled by springs 61 into seated position for preventing damage from "slugging."

In place of the springs 50 shown in Figs. 1 and 2, the casing 15 may be provided, as illustrated in Figs. 5 and 7 with an outwardly extending tubular housing 65, closed at its outer end by an end closure cap 66, having an internally threaded portion 67 in engagement with the threaded exterior of the housing 65, for adjustment.

A sealing bellows 68 is provided, connected at one end to the closure cap 66 in fluid tight relationship and connected at the other end in fluid tight relationship to an actuator plate 69. The interior of the bellows 68 is preferably vented to the atmosphere through a restricted port 70 in a cap plug 71 mounted in the closure cap 66, and the exterior of the bellows 68 is in communica-

tion with the interior of the casing 15 through a port 71, preferably restricted. Within the interior of the bellows 68 the unloading spring 50^a is provided. The actuator plate 69 is preferably provided with an internally threaded boss 72 for attachment, if desired, of an actuating rod (not shown) for actuation by any desired actuator, the plug 71 being removed for this purpose.

The cam elements 46 may be guided in their transverse movement by a guide sleeve 73 movable in the housing 65, and adjustable limit stops 49^b may be provided in the casing 15.

Referring now more particularly to Figs. 8 to 12, inclusive, a double pivoted mounting may be provided for the cap ring 40 which includes the trunnion pins 42 and 43 carried by an end wall plate 80 mounted in a sleeve 81 in the casing 15. The pins 42 are mounted in blocks 82 slidable in arcuate guide ways 83 in the sleeve 81 and the pins 43 are mounted in blocks 78 slidable in guide ways 84, also mounted in the sleeve 81.

The bearing 23 may also be mounted in the end wall plate 80 and adjusted endwise to adjust the rotor clearance by means of studs 79. The end wall plate 80 and the sleeve 81 are held in position by radially disposed studs 85. An end closure plate 86 may be mounted outside the end wall plate 80. The end wall plate 80 may be provided with parallel guide slots 49.

Interposed between the plate 80 and the cam elements 46 a pair of flexible metallic bellows 87 may be provided, closed at their lower ends by an actuator plate 88 in engagement with the cam elements 46 and closed at their upper ends by abutment plates 89 in abutting relation to the plate 80. The plate 80 is provided with a fluid passageway 90 in communication with the interiors of the bellows 87 through restricted openings 91 in the abutment plates 89 and may be connected by a fluid connection 92 to a pilot cylinder 94. The pilot cylinder 94 has mounted therein an adjustable head 93 and a pilot piston plate 95, to which one end of a flexible metallic bellows 96 is secured in fluid tight relationship.

The other end of the bellows 96 is secured in fluid tight relationship to an abutment plate 97. A compression spring 98 is provided, interposed between the cylinder head 93 and the piston plate 95. A plug 99, having a restricted opening 100 therein may be provided for closing the end of the cylinder 94. The piston plate 95 may be provided with a threaded boss 101 for engagement by an actuator rod (not shown) upon removal of the plug 99.

The cylinder 94 may be placed at any desired location and the system which includes the bellows 96, the fluid connection 92, and the bellows 87 may be filled with fluid, compressible or incompressible, as desired.

The fluid connection 92 may also be provided with a three-way valve 102 in communication with a fluid conduit 103 for connection to any preferred source of pressure for direct fluid pressure operation, if desired, of the bellows 87.

The mode of operation will now be pointed out.

It will be noted that the stroke of the pistons 31, upon rotation of the rotor 26, is determined by the positioning of the cap ring 40. When the cap ring 40 is substantially perpendicular to the shaft 22, so that the cam elements engage the limit stops 49^a or 49^b, a very short stroke of the pistons 31 is available and as the cap ring 40 is shifted angularly the stroke of the piston 31 is increased, with increase of load or as determined

by the force applied on the cam elements 46, as hereinafter more fully explained.

When the compressor is at rest the springs 50 in Figs. 1 and 2, the springs 50^a in Figs. 5 and 7, or the bellows 87 in Figs. 8 and 11 are normally expanded so that the cam elements 46 are moved downwardly to a position to shift the cap ring 40 to provide a minimum stroke.

Upon rotation of the shaft 22, and the rotor 26 carried thereby, the terminal ends 29 of the bores 27 are successively advanced past the inlet port 19 in the valve plate 18 and the delivery or discharge port 20 in the valve plate 18. The pistons 31 are positioned by the cap ring 40 so that they are at the rod ends of their strokes as each cylinder bore 27 moves beyond the end of the inlet port 19 and at the head or valve plate end of their strokes as they move beyond the end of the delivery port 20.

Fluid in the bores 27 as the successively advance between the ports 19 and 20 is compressed in the working chambers in the bores 27.

Referring now to Figs. 1 to 4, inclusive, the compressor is unloaded at starting. As the pressure in the working spaces increases, the force therefrom is effective through the piston rods 34 against the cap ring 40 and therefrom through the lugs 45 against the cam elements 46 and therefrom against the force exerted by the springs 50 until and during operation at full stroke. When the compressor stops the pressure is equalized between the inlet and the outlet and the springs 50 return the cam 46 to its unloaded position.

The use of a rotor and valve plate permits of high speed operation and the reduction of clearance in the bores 27 reduces re-expansion losses.

Referring now more particularly to Figs. 5, 6 and 7, in the form of compressor there shown provision is made for unloading at starting and the compressor also adjusts itself to the load within the limits of its capacity. The capacity adjustment is gradual or modulated by reason of the action of the spring 50^a, the cam 46, and by the spring action of the bellows 68, and the restriction 70 provides a dash pot effect with the spring 50^a separated and the remainder of the compressor sealed therefrom. The spring 50^a may also be adjusted by turning the cap 66.

An equalizer connection 76 is provided in communication with the suction line so that the inlet pressure is effective within the interior of the casing 15.

If desired, the plug 71 may be removed and the desired force application made through the boss 72 by any desired metering device (not shown), temperature, humidity or otherwise responsive, as preferred.

Lubrication is provided through the slot 55, grooves 56 and passageways 57.

If the pressure should become excessive the relief valves 60 are available for by-passing fluid to the delivery port 20.

Referring now more particularly to Figs. 8 to 12, inclusive, the unloading spring 98 is exteriorly disposed with respect to the casing 15. The interior of the bellows 87 and 96 and the fluid connection therebetween may be filled with liquid, or with gas under pressure, to provide a fluid link between the bellows 87 and the bellows 96 and with the restriction 100 acting in a manner similar to restriction 70. If desired also, the plug 99 may be removed and an actuator (not shown) connected to the boss 101 for control from a metering element (not shown).

If pressure fluid application against the bellows 87 from an exterior source of fluid under pressure is desired, the valve 102 may be positioned for access of fluid through the fluid connection 103 in either direction.

In the compressor as illustrated in Figs. 5 to 12, inclusive, the inlet pressure may be varied, as desired, over a wide range from sub-atmospheric pressure to pressures of the order of fifty pounds.

10 The inlet pressure is effective through the equalizing connection 76 and in opposition to that effective in the interior of the bellows 68 or the bellows 87.

I claim:

15 1. In a compressor, a tubular casing, a valve plate in said casing and having an interior face with fluid inlet and fluid delivery ports therein, a rotor in said casing in facing relation to said valve plate and having a plurality of longitudinal bores for respective register with said ports, pistons reciprocable in said bores, a ring member, piston rods connected to said ring member and to said pistons, pivotal mounting means for said ring member the pivotal axis of which is coincident with the pivot of one of said piston rods at said ring member for one dead center position of said one of said piston rods, an abutment member on said mounting means, a transversely movable cam member in said casing for positioning said ring member and resilient means for impelling said cam member.

20 2. In a compressor, a tubular casing, a valve plate in said casing and having an interior face with fluid inlet and fluid delivery ports therein, a rotor in said casing in facing relation to said valve plate and having a plurality of longitudinal bores for respective register with said ports, pistons reciprocable in said bores, a ring member, piston rods pivotally connected to said ring member and to said pistons, pivotal mounting means for said ring member the pivotal axis of which is coincident with the pivot of one of said piston rods at said ring member for one dead center position of said one of said piston rods, an abutment on said mounting means, a transversely movable cam member having an angularly disposed face for engagement with said abutment for positioning said ring, and resilient means for impelling said cam member for varying the stroke of the pistons.

25 3. In a compressor, a tubular casing, a valve plate closing one end of said casing and having an interior face with fluid inlet and fluid delivery ports therein, a closure member at the other end of said casing, a longitudinally extending shaft in said casing, a rotor on said shaft in facing relation to the interior face of said valve plate and having a plurality of longitudinally disposed cylinder bores for respective register with said ports, pistons reciprocable in said bores to and from said valve plate, a ring member, piston rods pivotally connected to said ring member and to said pistons, pivotal mounting means for said ring member, an abutment member on said mounting means, a transversely movable cam member mounted on said closure member and having an angularly disposed face for engagement with said abutment for positioning said ring, and resilient means for impelling said cam member.

30 4. In a compressor, a tubular casing, a valve plate in said casing having an interior face with arcuately disposed fluid inlet and fluid delivery ports therein, a rotor in said casing in facing relation to the interior face of said valve plate

and having a plurality of longitudinal bores for respective register with said ports, circularly disposed fluid sealing members interposed between said valve plate and said rotor, pistons reciprocable in said bores, a ring member, piston rods pivotally connected to said ring member and to said pistons, pivotal mounting means for said ring member, an abutment on said mounting means, a movable cam member having an angularly disposed face for engagement with said abutment for positioning said ring, and means for impelling said cam member.

5. A compressor as defined in claim 1 in which the pivotal mounting means comprises pins carried by the casing.

6. A compressor as defined in claim 1 in which the pivotal mounting means comprises aligned pins journaled in the casing and providing a pivotal axis offset from the axis of the rotor.

7. A compressor as defined in claim 1 in which the pivotal mounting means includes trunnions at the pivotal axis and pivots having their axes intersecting and normal to the axis of rotation of the rotor.

8. A compressor as defined in claim 1 in which the pivotal mounting means includes trunnions at the pivotal axis mounted in arcuate guideways and pivots having their axis intersecting and normal to the axes of rotation of the rotor mounted in longitudinally extending guideways.

9. A compressor as defined in claim 1 in which the fluid delivery port has in communication therewith a resiliently impelled relief valve for the delivery of excess fluid in the bores to said delivery port.

10. A compressor as defined in claim 1 in which the fluid delivery port includes a passageway having interposed therein a resiliently impelled relief valve for the delivery of excess fluid in the bores to said delivery port.

11. A compressor as defined in claim 1 in which a rotor enclosing sleeve is mounted in the casing having lubricating passageways extending to the valve plate, and the valve plate has lubricating

passageways in communication with the facing portions of the valve plate and the rotor.

12. A compressor as defined in claim 1 in which the resilient impelling means includes a fluid pressure responsive member in actuating relation to said cam member and fluid connections in communication with said pressure responsive member for applying fluid pressure thereagainst.

13. A compressor as defined in claim 1 in which a fluid connection is provided in communication with the interior of the casing and with the fluid inlet connection, and in which the resilient impelling means includes a fluid pressure responsive member against which the pressure in the interior of the casing is effective.

14. A compressor as defined in claim 1 in which a fluid connection is provided in communication with the interior of the casing and with the fluid inlet connection, and in which the resilient impelling means includes a fluid pressure responsive member against which the pressure in the interior of the casing is effective, and variable means for applying a pressure against said fluid pressure responsive member in opposition to the interior pressure.

15. A compressor as defined in claim 1 in which the resilient impelling means includes a fluid pressure responsive member in actuating relation to said cam member, a second fluid pressure responsive member, fluid connections between said pressure responsive members, and a resilient loading member in engagement with said second pressure responsive member.
